DESIGN FOR A TABLE

William E. Reynolds, Oak Ridge, Tenn.

Application June 11, 1946, Serial No. 130,614

Term of patent 7 years

(Cl. D33—14)

To all whom it may concern:

Be it known that I, William E. Reynolds, a citizen of the United States, residing at Oak Ridge, in the county of Anderson and State of Tennessee, have invented a new, original, and ornamental Design for a Table, of which the following is a specification, reference being had to the accompanying drawing, forming a part thereof.

Figure 1 is a top plan view of a table, showing my new design.

Figure 2 is a front elevational view.

Figure 3 is an end elevational view.

Figure 4 is a sectional view taken along the line 4—4 of Figure 1.

Figure 5 is a bottom perspective view.

I claim:

The ornamental design for a table, as shown.

WILLIAM E. REYNOLDS.
